(57) **CLAIM**

The ornamental design for an illuminated voltage sensor, as shown and described.

DESCRIPTION

FIG. 1 is a perspective view of the illuminated voltage sensor.

FIG. 2 is a top plan view of the invention.

FIG. 3 is a left side elevational view of the invention.

FIG. 4 is a right side elevational view of the invention.

FIG. 5 is a bottom plan view of the invention.

FIG. 6 is a rear plan view of the invention; and,

FIG. 7 is a front plan view of the invention.
